UNITED STATES PATENT OFFICE.

ELMER R. CONNOR AND CHARLES W. VOELPEL, OF PORT RICHMOND, AND JOSEPH M. CONNOR, OF NEW YORK, N. Y.

GARMENT-HANGER.

1,184,724.

Specification of Letters Patent.

Patented May 30, 1916.

Application filed June 3, 1915. Serial No. 31,840.

To all whom it may concern:

Be it known that we, ELMER R. CONNOR, CHARLES W. VOELPEL, and JOSEPH M. CONNOR, all citizens of the United States, the 5 said ELMER R. CONNOR and CHARLES VOELPEL residing at Port Richmond, Richmond county, State of New York, and the said JOSEPH M. CONNOR residing in the city, county, and State of New York, have invented 10 certain new and useful Improvements in Garment-Hangers, of which the following is a full, clear, and exact description.

This invention relates to an improvement 15 in garment-forms or hangers designed for the purpose of supporting dresses, coats, suits or the like.

The particular object of this invention is to provide a foldable hanger arranged to 20 support garments for the purposes of display or for the purpose of hanging said garments in a closet or the like.

One of the chief features of our invention is the manner of folding the hanger 25 elements which can be accomplished by pulling a rod or wire which in turn actuates other rods or wires connected to the foldable elements of the hanger. The frame for said foldable elements being arranged 30 so that it can also be folded after the other elements, which are carried by the frame, are folded.

Other features of improvement will hereinafter be pointed out.

35 We will now proceed to describe our invention in detail, the novel features of which we will point out in the appended claims, reference being had to the accompanying drawing forming part hereof, wherein—

40 Figure 1 is a side elevation of a garment-hanger embodying our improvement; Fig. 2 is a sectional plan view thereof, the section being taken on a line 2—2 in Fig. 1; Fig. 3 is a front view of the hanger, the body members being shown as folded; Fig. 4 is an enlarged perspective view showing the hinge, or pivotal connection, employed to form the 45 two frame members, and Fig. 5 is a similar view showing the pivotal connection employed to join the lower end of the lower frame members to the lowermost body member.

As herein illustrated our improved hanger 55 comprises a frame consisting of a plurality of members 1 and 2 hinged or pivotally con-

nected at 3. The upper frame-member 1 comprises the side members 1^a, 1^a and end bar 4, which connects the said side members. The frame member 1 will be made out of a single strand of wire having a loop 5 at its 60 lower ends which engages the lower frame member 2. The lower frame member 2 comprises the side members 2^a, 2^a and end bar 6. The end bar 6 and side members 2^a, 2^a are made out of a single strand of wire. 65

One of the features of our invention is the manner of holding the frames in alignment when extended for use, which we accomplish by forming retaining arms 7 out of the strand, which forms the frame member 2. To form the arms 7, we double the 70 said strand of wire upon itself and carry the doubled portion upwardly and then flare each doubled strand outwardly as shown in Fig. 4. By curving the flared portion of 75 the strand and recessing same as at 8, we provide a retaining arm to engage the side members of the upper frame when said frame is extended for use. When the frame 1 is extended it will bear against the retaining arm 7.

Each side member 1^a, 1^a and 2^a, 2^a is provided with an eye 9, 9 and 10, 10 respectively, to pivotally support body members in the form of rings 11 and 12. The lower end 85 of each side member 2^a, 2^a pivotally engages a body member or ring 13, an eye 14 being formed, at the lower end of each side member 2^a, for this purpose. To cause the side members 2^a, 2^a to firmly grip the lower body 90 member, we provide a cross-bar 15 which is secured to said side members, and which tends to pull said side members inwardly.

As will be seen in Fig. 5, each eye 14 is elongated and engages a trunnion 15^a on the 95 body member 13. The trunnion 15^a consists of a plurality of diverging extensions of the strand which forms the lower body member, the said extensions being indicated by 16; the said extensions terminate in a hook 17, 100 to act as guard for the side members 2^a. The length of the loop 14 is slightly less than the distance between the extensions 16 at the widest part but greater than the distance between said extensions at the narrowest 105 part. Hence when said side members spring apart, the body member 13 is free to be rotated for folding. When the body members are extended for use, the rotation of the lower body member will cause the exten- 110

sions 16 to jam or become wedged in the loop 14, thereby holding the said body member 13 firmly in position, the retaining arm 7 holding the upper frame member 1 firmly 5 in position.

To actuate the body members 11, 12 and 13, for extension or for folding, we employ links 18 and 19 which are actuated by a pull-rod 20, the said pull-rod being guided by an 10 eye 21 formed in the cross-bar 4 of the frame 1. The link 18 is connected to a connecting rod 22, which in turn connects the body members 12 and 13, and the pull rod 20. The link 19 is connected to the said pull-rod 20 15 and upper body member 11, all of said connections being pivotal.

Should the body members be extended as shown in Fig. 1, an upward pull upon the rod 20 will fold said members to lie in parallelism with the frame members 1 and 2. 20 After which the said frame members can be folded over to lie in contact one with the other due to the pivotal connection at 3. By these means we are enabled to produce a garment hanger that can be folded for packing into a suit case or box. To extend the hanger for use, the above described operation will be reversed.

Our improved hanger will be found very 30 useful for salesmen for exhibiting dresses or garments as it can be readily set up for use or packed away. The hanger can be hung upon a hook or nail, or stood upon a table.

35 As our improved hanger is made entirely of wire, it is very light and durable besides being rigid when extended for use, due to the retaining arms 7 and yieldable extensions 15^a.

40 While we have shown the body members 11, 12 and 13 as round, they may be square if desirable; in fact, the whole hanger can be made in any shape desirable.

Having now described our invention, what 45 we claim and desire to secure by Letters Patent is:

1. A garment-hanger comprising a frame consisting of a plurality of pivotally connected members, a body member pivotally 50 secured at opposite points thereof to the upper frame member, a plurality of body members pivotally secured at opposite points thereof to the lower frame member, a pull rod, and independently acting links connect-

ing said pull-rod and said body members, 55 said body members when positioned for use extending beyond each side of said frame.

2. A garment-hanger comprising a frame consisting of a plurality of pivotally connected members, a body member pivotally 60 secured to the upper frame member, a plurality of body members pivotally secured to the lower frame member, a pull rod, links connecting said pull-rod and said body members, and means independently of said pull-rod and links to lock the frame members in 65 extended position.

3. A garment-hanger comprising a frame consisting of a plurality of pivotally connected members, a body member pivotally 70 secured to the upper frame member, a plurality of body members pivotally secured to the lower frame member, a rod pivotally connecting the body members carried by the lower frame member, a pull-rod supported 75 by the upper frame member, a link connecting the pull-rod and the upper frame member, and a link connecting said pull-rod and the rod connecting the frame members carried by the lower frame member.

4. A garment-hanger comprising a frame consisting of a plurality of pivotally connected members, means located at the pivot points of said frame members arranged to lock said frame members in an extended position, a plurality of foldable body members carried by said frame members, and means to operate said body members in unison. 80

5. A garment-hanger consisting of a plurality of pivotally connected frame members, 90 each frame member consisting of a single strand of wire bent into suitable shape, the strand forming the lower frame member being doubled upon itself at two opposite points to form retaining arms, the strand forming the upper frame member being formed into eyes at its free ends to pivotally engage the strand forming the lower frame member, and foldable body members carried by said frame members. 95

Signed at New York city, N. Y., this 25th day of May 1915.
